Attorney.

UNITED STATES PATENT OFFICE.

WILLIAM E. BERENS, OF BUFFALO, NEW YORK, ASSIGNOR OF ONE-HALF
TO CHARLES MAYER, OF SAME PLACE.

COCK-GRINDING MACHINE.

SPECIFICATION forming part of Letters Patent No. 286,525, dated October 9, 1883.

Application filed July 26, 1883. (No model.)

To all whom it may concern:

Be it known that I, WILLIAM E. BERENS, of Buffalo, in the county of Erie and State of New York, have invented certain new and useful Improvements on Cock-Grinding Machines; and I do hereby declare that the following description of my said invention, taken in connection with the accompanying sheet of drawings, forms a full, clear, and exact specification, which will enable others skilled in the art to which it appertains to make and use the same.

My present invention has general reference to cock-grinding machines; and it consists, essentially, in the novel and peculiar combination of parts and details of construction, as hereinafter first fully set forth and described, and then pointed out in the claims.

In the drawings already mentioned, which serve to illustrate my said invention more fully, Figure 1 is a front elevation, and Fig. 2 a rear elevation, of my improved machine for grinding cocks and faucets. Fig. 3 is a side elevation of the same. Figs. 4, 5, and 6 are detail views, on a larger scale, of the mechanism for regulating the height of the cock-holding device. Figs. 7 and 8 are detail views of the chuck for holding the plug and the clamping device for retaining the cock or faucet body. Fig. 9 is a plan and transverse sectional elevation of the body-clamp detached. Fig. 10 is a transverse sectional view of a friction device applied to shaft G. Fig. 11 is a plan of the clamping device for the body-clamp, showing the latter in a clamped position. Fig. 12 is a similar view, illustrating the clamp in a disengaged position.

Like parts are designated by corresponding letters of reference in all the figures.

The object of my present invention is the production of a simple and effective machine for grinding cocks and faucets in a manner similar to that now employed by brass-finishing. To attain this end, I construct my cock and faucet grinding machine essentially of a suitable frame, A, having a bed or table, B, carrying standards C C', D D', respectively, the former pair being provided with journals for the reception of the spindle E, carrying the cone-pulley F, and the latter pair being adapted to receive the spindle G, having the chuck H.

Upon one end of the shaft E is fitted an eccentric, K, connecting with a crank, L, on the shaft G by means of a connecting-rod, M. Rotary motion being communicated to the cone-pulley in any desirable and well-known manner, this motion is, by means of the eccentric and the crank mentioned, converted into a vibratory or rocking motion in the shaft G, which motion is so devised as to be always somewhat less than one-half of a revolution.

On the forward part of the frame A are provided two cheeks, M M', respectively, in the jaws m of which are fitted boxes or bearings O O', receiving a shaft, P, to which a frame, Q, made preferably of wrought-iron pipe, owing to its lightness and strength, is affixed in any suitable manner. This frame Q has a rod, Q', carrying on each end a handle, R, whereby said frame is actuated and manipulated in a manner as hereinafter more fully referred to. This frame Q is vertically adjustable by the sliding boxes O O', and these are locked in any position within the compass of the vertical movement of said boxes O O' by means of locking-segments S S', fixed to a treadle crank-shaft, T, so that by depressing said treadle shaft the locking-segments will liberate the boxes O, while a suitable spring, U, will raise said treadle as soon as liberated, and thus again lock the said boxes O. In order to balance the weight of the frame Q and its accessories, I provide springs V, or a similar suspending device, to uphold said boxes O, while, to prevent said frame from falling over, I attach a spiral spring, q, to said frame and connect it with any part of the table B, as clearly shown in the figures.

To the upper bar or rod, Q', of the frame Q is removably affixed a cock or faucet clamp, X, Figs. 8 and 9, consisting, as usually made, of two pieces of wood hinged together, if desired, and recessed in their meeting surfaces, so as to receive the cock or faucet Y between them when said clamp is closed, a locking device, Z, Fig. 8, consisting of a hook and eye, Z Z', respectively, or any other suitable mechanism, being provided to keep said clamp in a closed position, while another clamping mechanism, constructed, essentially, of a hooked-shaped fastening, 2, and a cam-shaped lever, 1, pivoted to the under side of one part of the body-clamp

X at 3, Figs. 8, 10, and 11, serves to retain the body-clamp X in proper position upon the rod Q'. This pivoted cam-shaped lever, when occupying the position shown in Fig. 11, holds 5 the body-clamp X securely to the rod Q', yet not so tight but that said body-clamp can be revolved somewhat around said rod Q', if necessary, to bring the axial line of the faucet-body into coincidence with the plug y in the chuck 10 H. When turned into the position shown in Fig. 12, the body-clamp is liberated, and may be removed from the machine, to remove the faucet and replace it by another one, as often as necessary.

15 The machine heretofore described is capable of grinding all the different kinds and sizes of faucets in the market, each kind or size requiring a different body-clamp. These clamps are therefore required to be of various thicknesses, 20 and in order to enable the various size of faucets, &c., being brought in line with the axial line of the shaft G the frame Q is rendered vertically adjustable, as heretofore described, and when adjusted to any desired position is retained in that position by the foot-lever T, with the cams S acting upon the boxes O O' of the shaft P, supporting the frame Q, all as hereinbefore set forth and described.

25 In operation the faucet Y is placed into the faucet-clamp X, and the latter secured to the rod Q' of the frame Q. Now, the plug y, Fig. 8, is clamped in the chuck H and the machine set in motion, whereby said plug y is caused to rock or oscillate in a manner readily comprehended. Now, a suitable abrading substance, 30 consisting, usually, of very fine yellow sand mixed with soap and water into a paste of the consistency of cream, is applied to the plug, and then the body of the faucet pushed lightly 35 and gradually onto the said plug and pulled off again, the operation being repeated very frequently, so as to prevent the plug from binding in the body, which would cause "cutting" or creases to appear, and thereby render the 40 faucet, &c., useless. When a sufficient grinding has taken place, the plug and faucet are 45 "washed" to examine the progress in grinding, and when the plug is found to bear perfectly in the body these parts are removed from the 50 machine and others inserted.

55 It will now be readily observed that the action of this machine is precisely like that now performed by a mechanic when grinding cocks and faucets, the only difference being that in the process of grinding cocks by hand the plug is held stationary and the body actuated, while in my present machine the body remains stationary, as it were, and the plug is vibrated.

60 In order not to keep the plug in the same position while the grinding is taking place, I may provide the chuck H with suitable means for self-centering the plug, so that I can remove the same and turn it around sufficiently to present the plug to the faucet in different 65 positions; or I may make the shaft G in two parts and connect these parts by means of

clutch mechanism, substantially as shown in Fig. 10, where the shaft G G" is illustrated as provided on adjacent ends with flanges 4 5, respectively, having between them a disk, 6, 70 of flexible material, said flanges being drawn together by set-screws 8 in the casing 7, as clearly shown in said Fig. 10, or by any other suitable mechanism, so that one part of said shaft may be revolved while the other remains 75 fixed, and thus produce the desired result in an expeditious manner. This clutch mechanism is, furthermore, of advantage, because it would cause the plug to remain at rest should it become locked or "tight" in the body while 80 grinding takes place, from any cause whatever, until the machine can be stopped or the faucet pulled off the said plug. The shaft G is inclined with reference to the shaft E, the inclination being downward toward the front 85 side of the machine. This is quite an essential feature in cock-grinding machines, because it prevents the grinding substance from flowing off the plug or out of the body, the inclination being such that the lower side of the 90 tapering plug is horizontal.

95 It is perfectly evident that a different clamp X is required for every different faucet-body, and that any kind of a chuck H that may be found to answer the purpose may be used in this machine in place of the chuck shown. So may other different clamping mechanism be used for attaching the cock-clamps X to the actuating-frame Q without changing the nature of my invention, such changes in the details of the mechanism being readily made as 100 circumstances require.

105 In the drawings I have shown mechanism for converting the rotary motion of the shaft E into a rocking motion of the shaft G, such conversion being accomplished by the eccentric, the "throw" of which is less than that of the crank on said shaft G. It is perfectly obvious, however, that any other mechanism for converting rotary into oscillating motion 110 may be employed without changing the nature of my said invention, such mechanism being well known and in common use on many different machines, engines, &c., and need not, therefore, be here described as equivalents for 115 the mechanism specified.

120 The operation of grinding cocks and faucets by hand without the aid of machinery is a very slow and tedious one, and by brass-finishing is shunned more than any other work 125 connected with their trade. Any machine that will do this part of the brass-finisher's work perfectly cannot but be a welcome tool in brass-finishing establishments, and my present machine, being simple in construction and operation and very inexpensive as far as its cost is concerned, will, on these accounts, be within the reach of all who have use for a machine of the class described.

130 Having thus fully described my invention, I claim as new and desire to secure to me by Letters Patent of the United States—

1. In cock-grinding machines, the adjustable frame, combined with the body-clamps, substantially as described, said body-clamps being removably secured to said frame in the manner substantially as described and stated.
2. The combination, with the frame A and table B, of the rocking-shaft G, having the chuck H for holding the faucet-plug, the adjustable frame Q, with the body-clamp X, and mechanism, substantially as described, for locking said frame in any desired position, said shaft G being fitted within suitable bearings on the machine, substantially as and for the object stated.
3. The combination, with the frame A, of the checks M M', having jaws m, boxes 'O, frame Q, and the locking device for said boxes, substantially as described, for the object mentioned.
4. In cock-grinding machines, the adjustable mechanism for holding and actuating the faucet-body, consisting, essentially, of an adjustable frame having suitable handles, and a clamp to embrace said body, said clamp being removably affixed to said frame in a manner substantially as specified, for the object stated.
5. In cock-grinding machines, the adjusta-
- ble mechanism for holding and actuating the faucet-body, consisting, essentially, of the frame Q, having the rod P, fitted with boxes O O', movably secured within the jaws m of the cheeks M M', crank-treadle T, locking-segments S, and means, substantially as specified, for actuating the crank-treadle, as and for the purpose indicated.
6. In cock-grinding machines, the oscillating shaft having the chuck for holding the faucet-plug, in combination with the friction-clutch on said shaft, substantially as specified, for the object stated.
7. In cock-grinding machines, the combination, with the shaft E, having the driving-pulley F, of the shaft G, with chuck H and friction-clutch, as described, eccentric K, connecting-rod N, crank L, and the adjustable frame Q and locking device for said frame, the whole being constructed and combined substantially as and for the object stated.

In testimony that I claim the foregoing as my invention I have hereto set my hand in the presence of two subscribing witnesses.

W. E. BERENS.
